UNITED STATES PATENT OFFICE.

I. B. LIVINGSTON AND M. WATERHOUSE, OF BARNET, VERMONT.

MACHINE FOR FEEDING PAPER TO PRINTING-PRESSES.

Specification of Letters Patent No. 12,761, dated April 24, 1855.

To all whom it may concern:

Be it known that we, ISAAC B. LIVINGSTON and MILES WATERHOUSE, of Barnet, in the county of Caledonia and State of Vermont, 5 have invented a new and useful Machine for Feeding Paper to Printing-Presses; and we do hereby declare that the following is a full, clear, and exact description of the construction and operation of the same, reference being had to the annexed drawings, 10 making a part of this specification, in which—

Figure 1 is a perspective view. Fig. 2 a ground plan of machinery for raising the 15 paper table, Fig. 3 a view of one of the angular guide ways.

A, A, is the bed plate. B, B, sides attached to said plate.

C is an exhausting apparatus as a bellows 20 or air pump or their equivalents.

D, D, are tubes attached to the exhausting apparatus, these tubes to be made of any suitable material.

E, is a crossbar attached to the tubes near 25 their lower end to retain them at their proper distance from each other, and having each end fitted so as to move in the angular guide ways.

F, F, are angular guide ways in which the 30 end of crossbar E moves and are attached to sides B, B.

G, G, are levers attached to crossbar E, the other ends are attached to two sliding boxes by a pivot on which they vibrate.

H, H, are the sliding boxes to which the 35 levers G, G, are attached.

I, I, are parallel ways on which the boxes H, H, slide.

a a are arms of peculiar construction at 40 tached to levers G, G, between which the crank K operates to push forward, fetch back, and raise up said levers.

K is a compound crank, one part working 45 between arms a a the other operates the exhausting apparatus C.

b, is a crosshead attached to top of exhausting apparatus as a bellows or piston to pump.

C, C, are connecting rods, connecting 50 crank K, with the cross head b.

N (Fig. 2) is the driving shaft, having spur gear W, which meshes into the intermediate S, and has a bevel gear at or near the other end.

M is a shaft driven by shaft N, by bevel 55 gear and having a screw at the other end.

L is a shaft having bevel gears at each end, and spur gear in center in which the screw on shaft M works.

g, g, are shafts to which cams f, f, f, f, 60 are attached, and are worked by shaft L, being connected with it by bevel gears.

R, is a table resting upon the cams f, f, f, 65 upon which the paper is laid, and which is raised by machinery described so as to keep the paper to proper height for the tubes.

Operation: By turning crank x you give motion to shaft N, which is geared by the intermediate cog wheels to crank shaft K, 70 working between the arms a, a, attached to levers G, G, the crank K first strikes the top of the arm a which raises it and the lever and its attachments to its highest point and continuing its stroke presses against the side 75 of arm a, throwing or pushing the levers G, G, with tubes, and crossbar attached forward to the required distance along the guide ways F, F. K', K', is crank attached to the exhausting apparatus at about right 80 angles with crank K, so that when the levers have been raised, and carried forward to the required point the exhausting apparatus shall blow off the paper which was attached to the tubes, and when the crank K, has 85 pushed back the lever G, G, and allowed the tubes D, D, to drop upon the paper the crank K, will commence to operate the exhausting apparatus so as to exhaust the air 90 from the tubes D, D, which causes the paper to adhere to them by suction or atmospheric pressure the crank K, in the meantime has passed to top of arm a, raising the levers G, G, and their attachments and carrying them forward as described. At the same time 95 the ream of paper has been raised the distance of the thickness of that of paper by its machinery, viz: The shaft N, is driven by crank X, and by bevel gear drives the shaft M, the screw on shaft M, drives spur gear 100 on shaft L which by the bevel gear at each end moves the shafts g, g, and with them the cams f, f, f, f, and the table R, resting upon the face of the cams will be raised by them to the distance required.

What we claim as our invention and wish to secure by Letters Patent is—

1. We claim the use of the angular guide ways in combination with the crossbar or its equivalent.

2. We claim the use of crank or its equivalent working between the arms of levers

105

110

as described, in combination with levers and crossbar as described.

3. We claim the raising table in combination with the cams shafting and gearing 5 (for moving said table,) or their equivalents as described.

4. We do not claim the raising of paper by atmospheric pressure as that has been before used for that purpose.

But we do claim the combination of machinery as described for carrying forward the paper a sheet at a time and feeding it to printing presses. 10

ISAAC B. LIVINGSTON.
MILES WATERHOUSE.

In presence of—

J. A. JOHNSON,
J. H. JOHNSON.
